FREDRICK ZIEMER -

By H. S. Jaffe

Attorney

UNITED STATES PATENT OFFICE.

FREDRICK ZIEMER, OF FREEPORT, NEW YORK.

PENCIL ATTACHMENT.

1,224,992.

Specification of Letters Patent.

Patented May 8, 1915.

Application filed November 28, 1913. Serial No. 133,962.

To all whom it may concern:

Be it known that I, FREDRICK ZIEMER, a citizen of the United States, residing at Freeport, in the county of Nassau, State of New York, have invented a new and useful Pencil Attachment; and I do hereby declare the following to be a full, clear, and exact description of the invention, such as will enable others skilled in the art to which it applies to make and use the same.

The present invention relates to an eraser attachment for pencils which embodies novel features of construction whereby the pencil will not roll upon the floor if dropped on a desk, and will not roll into some inaccessible position if dropped upon the floor, thereby saving the large amount of time which is ordinarily spent in the aggregate in looking for lost pencils.

Further objects of the invention are to provide a device of this character which is comparatively simple and inexpensive in its construction, which can be readily placed upon a pencil or removed therefrom, which not only prevents rolling of the pencil but can also be used as an eraser, and which does not interfere with handling the pencil in the usual manner.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:—

Figure 1 is a perspective view of the reduced end of a pencil upon which the attachment is to be fitted.

Fig. 2 is a detached perspective view of the rubber attachment.

Fig. 3 is a side elevation of a pencil having the rubber attachment applied thereto, portions being broken away and shown in section.

Fig. 4 is a transverse sectional view on the line 4—4 of Fig. 3.

Corresponding and like parts are referred to in the following description and indicated in all the views of the drawings by the same reference characters.

Referring to the drawings, the numeral 1 designates a lead pencil which is of the conventional construction, one end of the pencil

being reduced and tapered, as indicated at 2. An annular seat 3 is provided at the base of the reduced and tapered stem 2, while longitudinal grooves 4 extend along diametrically opposite sides of the tapered stem 2. The rubber attachment includes an elastic sleeve 5 having a bore which is tapered to correspond with the taper of the stem 2, said bore being provided upon opposite sides thereof with internal ribs 6 for engagement with the grooves 4 of the stem 2, and being also provided at the mouth thereof with an internal enlargement 7 which is adapted to spring into the annular seat 3. The longitudinal ribs 6 thus coöperate with the grooves 4 to hold the sleeve against rotation upon the pencil, while the enlargement 7 engages the annular seat 3 to prevent the sleeve from being accidentally withdrawn from the pencil. The end of the sleeve carries a laterally enlarged head 8 which projects a considerable distance upon the diametrically opposite sides thereof and is formed with opposed and substantially parallel side faces 8^a which are arranged in such a manner as to make it impossible for the pencil to roll if accidentally dropped upon the floor or desk. The length of the flattened head is considerably greater than its thickness, and the ends of the flattened head may be slightly flared, if desired, and terminate at the sides thereof in points 8^b such as will prove very effective in engaging a flat surface to prevent rolling of the pencil thereon. With this construction it will be obvious that the attachment can be readily slipped upon a pencil or removed therefrom, and that when it is in operative position it can not only be used in the customary manner as an eraser, but will also prevent the pencil from rolling if dropped upon a flat surface.

It is well known that devices having similar objects in view have been constructed with square, triangular and polygonal shaped heads, but these heads are not effective in preventing the rolling of a pencil, because of the fact that the flat sides on the heads of these prior devices are all equal in size and consequently of a small area, thereby preventing a solid bearing of the head on a flat surface. In the present construction the flat faces 8^a are of a larger area and instead of being equal to the area of each of the other two faces are considerably greater. Thus, although when the pencil is carelessly thrown down or dropped on a flat surface

one of the smaller end faces might engage the surface temporarily, the bearing surface is so small, compared to the size of the head, that the pencil will immediately swing into 5 position with one of the larger faces of the head in engagement with the flat surface, and remain in this position until deliberately picked up and moved.

Having thus described the invention, what 10 I claim as new and desire to secure by Letters Patent, is:—

1. The combination with a pencil which terminates at one end thereof in a reduced stem, of an elastic sleeve slipped removably 15 upon the reduced stem and provided with a flattened head projecting in diametrically opposite directions from the sleeve and providing opposed and substantially parallel side faces to prevent rolling of the pencil on 20 a flat surface, the length of the head being considerably greater than its thickness so as to provide side faces having a large area and end faces having a small area.

2. The combination with a pencil terminating at the end thereof in a reduced and 25 tapered stem, said stem having longitudinal grooves in the sides thereof and an annular depressed seat at the base thereof, of a rubber sleeve fitted upon the stem and provided with interior longitudinal ribs for engagement 30 with the grooves of the stem as well as an annular inwardly-projecting enlargement for engagement with the seat at the base of the stem, said sleeve being formed with a flattened head which projects laterally therefrom in diametrically opposite directions and has spaced and parallel side faces 35 adapted to prevent rolling of the pencil on a flat surface.

In testimony whereof I have signed my 40 name to this specification in the presence of two subscribing witnesses.

FREDRICK ZIEMER.
